UNITED STATES PATENT OFFICE.

GORDON ANGUS ROSSBOROUGH, OF CHADWELL HEATH, ENGLAND.

CONVERTIBLE CHAIR.

Application filed March 10, 1924. Serial No. 698,321.

To all whom it may concern:

Be it known that I, GORDON ANGUS ROSSBOROUGH, a subject of the King of Great Britain, residing at 27 Gainsborough Road, 5 Chadwell Heath, Essex, England, have invented new and useful Improvement in Convertible Chairs, of which the following is a specification.

This invention relates to articles of furniture and refers more particularly to articles of furniture which can be used for a definite purpose and can be converted to form another article so as to be useful for a different purpose.

15 The movable portion of the chair is advantageously constituted by the seat and back of the chair.

In one constructional embodiment of the invention the improved article of furniture 20 regarded as a chair comprises four legs and top and bottom skeleton frames one of which serves as a base when the article is being used as a chair and both of which are adapted to act as supports and end walls 25 when the article is turned into position to form a cot. The chair legs are connected pairwise by cross slats to form the two sides and bottom of the cot and a portion of the top skeleton frame is formed as a movable tray 30 or support for the baby's toys or the like. The seat portion is pivoted or hinged to or near to the two front legs and the back portion is pivoted or hinged to the seat portion the arrangement being such that when it is 35 desired to form a cot the article is turned so as to be supported on the top and bottom skeleton frames and the seat portion turned on its pivots or hinges so as to form a part of the bottom of the cot the back of the seat 40 portion forming the end of the cot.

In order that the invention may be clearly understood and readily carried into effect I will now describe the same more fully with reference to the accompanying drawings 45 which illustrate several structural embodiments of the invention.

In these drawings:—

Figure 1 is a side elevation of one form of my improved article of furniture serving as 50 a baby's chair.

Figure 2 is a side elevation of the same article converted into a baby's cot.

Figure 3 illustrates a slightly modified form.

55 Figures 4 and 5 illustrate two further constructional forms having expanding

sides. Figure 4 illustrates the article actually serving as a cot.

The so-called chair-cot has four legs as usual, a top skeleton frame 1 formed with a 60 movable tray or support 2 for the baby's toys or the like, and a lower skeleton frame 3 serving as a base. The legs are suitably braced or stayed pairwise as to three pairs to constitute the two sides and bottom of the structure when acting as a cot as in Figures 65 2, 4 and 5. The forward ends of the side members of the bottom frame 3 are preferably provided with wheels, rollers, castors or the like 4 to facilitate moving the structure 70 about either as a chair or as a cot.

5 is the seat portion and 6 the back of the chair these parts being hinged together at 7 and the seat being hinged to the top front cross stay at 8 or alternatively pivoted 75 by means of bolts running through the main frame front legs at 8. 9 is a pad on the back of the chair which is attached to the top back cross stay by a hook or the like at 10. From inspection of the drawings it will be readily seen that the chair is converted into a cot by swinging the parts 5 and 6 into their alternative position in which the free end of the chair back is again attached to the top back 80 cross stay by a hook 11 or the like. Obviously instead of hooks any other convenient locking or fastening devices may be used. As will be readily understood the top and bottom skeleton frames of the chair 85 90 become the end walls and supports of the cot.

A three piece hinged mattress 12, 13, 14 may be attached to the bottom of the cot by means of tapes, clips or other suitable 95 fastenings so that when the cot is required to be converted into a chair this mattress may be folded over and remain within the chair. The enclosed space formed by the hinged mattress when folded may be suitably utilized to contain the child's pillow, 100 bedclothes and the like.

It is to be observed that the seat 5 projects beyond the front cross stays and beyond the rear edge of the tray 2 to ensure the baby's being retained on the seat. Figure 105 3 illustrates a slight modification in which the seat does not project much but the tray 2 extends back over the seat to a considerable extent represented by the hinged portion 2*, the function of the overlap being 110 the same as in Figures 1 and 2. In convert-

ing the chair shown in Figure 3 into a cot the hinged portion 2^a of the tray is folded back, and the seat is swung about pivots or trunnions 15 constituted by bolts passing through brackets or angle pieces 16 and through corresponding brackets extending downwardly from the underside of the seat.

In Figures 4 and 5 two ways of expanding the cot laterally are illustrated by way of example. In Figure 4 the sides of the cot are shown attached to the main structure by foldable arms 17 whilst in Figure 5 the sides are shown as constituted by cranked stays 18 and bar 19 the latter being in fact a back leg of the structure when serving as a chair. The entire row of cranked stays can swing outwards about their respective sockets and thereby add width to the cot, as will be readily understood. When in opened position the sides are held in any suitable manner, for example, by rod 20 and angle iron 21.

When laterally expandible sides are employed as shown in Figures 4 and 5, the longitudinal bars or "front chair legs" may be duplicated and cross braced to increase the strength.

If extra length is required the end wall at the foot of the cot that is to say the "chair back" portion of the structure can be let down from the position shown in Figure 2 into a horizontal position and be supported from the floor by a folding leg. This extension may receive an extra section 35 of the mattress or the pad on the seat back

may be detachable and be used as a mattress extension.

It will be understood that the above described constructions are not to be regarded as limiting the invention thereto but as indicating only the manner in which the invention may be carried into effect. Also any suitable material may be used in manufacturing the so-called chair-cot, as for example entirely square or round wood bars etc. or tubular metal or partly wood or partly metal.

What I claim is:—

1. An article of furniture convertible at will into a baby's cot or a chair comprising a framework, a chair-seat member hinged at its front edge to said framework, a chair-back member hinged at its lower edge to the rear edge of said chair-seat member and means for supporting said members in alternative chair-functioning and cot-functioning positions, so that the desired conversion may be effected.

2. An article of furniture convertible at will into a baby's cot or a chair comprising legs braced pairwise as to the front pair and the two side pairs, a seat member hinged as to its forepart to a cross brace of the front legs, a back member hinged to the rear part of said seat member, means for supporting said members in alternative chair-functioning and cot-functioning positions and means whereby the article may be expanded laterally when functioning as a cot.

GORDON A. ROSSBOROUGH
